No. 31,821.

PATENTED MAR. 26, 1861.

A. OSBORN.
QUILTING FRAME.

Witnesses:

Inventor:
Asahel Osborn

UNITED STATES PATENT OFFICE.

ASAHEL OSBORN, OF MORRIS, NEW YORK.

QUILTING-FRAME.

Specification of Letters Patent No. 31,821, dated March 26, 1861.

To all whom it may concern:

Be it known that I, ASAHEL OSBORN, of Morris, county of Otsego, and State of New York, have invented a new and useful Quilting-Frame; and I do hereby declare that the following is a full, clear, and exact description of the construction and operation of the same, reference being had to the annexed drawings, making a part of this specification, in which—

Figure 1 is a perspective view and Fig. 2 a transverse section.

A, A, A, Fig. 1, is the frame; B, B, B, arms; C C C C, slides on arms; D, D, dogs 15 which catch on the ratchet wheels S, S; E, E, rolls. F F F F are hooks or buttons to hold up the arms which are fastened to the frame by means of bolts or hinges.

Fig. 2, shows the position of the arms 20 when open and closed, or let down.

The frame may be made of wood or iron as also the arms. The rolls are made of wood.

By drawing the pins the slides may be moved back or forth on the arms to any 25 width desired.

By turning the hooks or buttons as seen in drawing at F F F F, the arms may be held firmly in their place or allowed to drop down as seen in Fig. 2.

What I claim as my invention and desire to secure by Letters Patent is—

The combination of the rolls E arms B slides C, with the frame A substantially as and for the purpose specified.

ASAHEL OSBORN.

In presence of—

Wm. A. E. GRAFTON,
A. S. AVERY.
